UNITED STATES PATENT OFFICE

172,695

CHRISTMAS TREE ORNAMENT

Robert Y. Allen and Melvin Shaw, Beverly Hills,
Calif., assignors to Hoover Products, Inc.,
Youngstown, Ohio, a corporation of Ohio

Application January 21, 1953, Serial No. 23,243

Term of patent 14 years

(Cl. D29—1)

To all whom it may concern:

Be it known that we, Robert Y. Allen and Melvin Shaw, citizens of the United States of America, residing at Beverly Hills, in the county of Los Angeles and State of California, have invented a new, original, and ornamental Design for a Christmas Tree Ornament, of which the following is a specification, reference being had to the accompanying drawing, forming a part thereof.

Figure 1 is a front elevational view of a Christmas tree ornament, showing our new design.

Figure 2 is a side elevational view thereof; and Figure 3 is a rear elevational view thereof.

We claim:

The ornamental design for a Christmas tree ornament, as shown.
